Primary Examiner—Alan P. Douglas*Assistant Examiner*—M. N. Pandozzi*Attorney, Agent, or Firm*—Phillips & Beumer**[57]****CLAIM**

The ornamental design for a dip tray for wetting the end of a cylindrical object, as shown and described.

DESCRIPTION

FIG. 1 is a top perspective view of my new design for a dip tray for wetting the end of a cylindrical object; FIG. 2 is a side elevational view thereof; FIG. 3 is a bottom planar view thereof; and, FIG. 4 is a sectional view thereof, taken along line 4—4 of FIG. 1.

The broken line showing of a stand in FIG. 2 is for illustrative purposes only and forms no part of the claimed design.

FIG. 1

FIG. 3

FIG. 2

FIG. 4
